UNITED STATES PATENT OFFICE

2,583,789

ELECTRIC FLASHER SWITCH

Jacques G. Mejean, Greenwich, Conn., assignor
to The Aerotec Corporation, Greenwich, Conn.,
a corporation of Connecticut

Original application March 27, 1946, Serial No.
657,579, now Patent No. 2,476,106, dated July
12, 1949. Divided and this application April
30, 1949, Serial No. 90,699

4 Claims. (Cl. 200—90)

1

My present invention relates to an electric make and break mechanism or "flasher."

In the flasher of my invention the intervals in which the circuit is opened and closed or is reversed are regularly and evenly spaced and their frequency is not sensitive to variations in voltage, nor to changes in position.

This application is a division of my Patent No. 2,476,106 of July 12, 1949.

The intervals of make and break are governed, in my invention, by a rocking or swinging arm or lever the periods of oscillation of which depend on the dimensions of the arm and not on the amplitude of swing or the force which acts on it. A swinging impulse is given to the arm by a hammer actuated by an electro-magnet in a circuit which is broken as the arm swings in one direction under the impulse. A spring returns the arm in a reverse swing and closes the circuit whereupon the action is repeated.

The various features of the invention are illustrated in the accompanying drawing in which

Fig. 1 is a plan view of a flasher embodying a preferred form of the invention, and Fig. 2 is a section on line 2—2 of Fig. 1.

In the embodiment of the flasher shown in the drawings, an insulated rocking arm 10 is mounted between pointed pivot pins 11 and 12 between supporting plates 13 and 14 in a housing or enclosing case 15. A pair of spring contact arms 16 and 17 are mounted on the rocking arm 10 in position to contact in alternate succession one or more fixed contacts 18 and 19 of a circuit.

The spring contacts 16 and 17 are connected by suitable connectors, not shown, to one pole of a battery or other source of electric energy.

The contacts 18 and 19 are supported on separate insulated spring arms 20 and 21 respectively connected to separate insulated binding posts 22 and 23 to which the opposite poles of the battery may be connected.

A spring 24 bearing against the rocking arm 10 serves to press the contact 17 against the spring arm 21 and contact 19.

A solenoid 25 in the housing 15 is provided with a rocking armature 26 pivoted at 27 and having a hammer 28 so positioned above the arm 10 that when a momentary current is sent through the solenoid and the armature 26 is attracted the hammer 28 kicks or hits the rocking arm 10 so as to rock it counterclockwise, separating the contacts 17 and 19 and closing the contacts 16 and 18. The spring 24 then returns the arm 10 to its original position to be again kicked or hit

2

by a subsequent impulse of current through the solenoid 25.

Inasmuch as the arm 10 is balanced it acts similarly to a pendulum and has a natural period of swing and is, therefore, not sensitive to changes in the intensity of the blow of the hammer 28 and its period of rotation or vibration is thus not substantially affected by changes in the voltage through the solenoid 25. Also being balanced it is not affected by vibrations or changes in position.

The effect of a stronger impulse or blow from the hammer 28 merely causes the arm 10 to swing in a somewhat wider arc but without substantial change in frequency.

What I claim is:

1. An intermittent switch which comprises a balanced rocking arm, an electro-magnet having an armature, a hammer actuated by said armature to kick said arm in one direction, a spring means pressing continuously on said arm to return said arm in the opposite direction and a circuit through said armature having contacts which are opened when said arm is kicked in one direction by said hammer and which are closed when said arm rocks in the opposite direction.

2. An intermittent switch comprising a pair of spaced contacts, a balanced rocking arm having contacts to contact said spaced contacts alternatively as said arm rocks in opposite directions, an electromagnet having an armature and a hammer actuated thereby to kick said arm in one direction to connect one pair of contacts and to separate the other pair of contacts and spring means pressing on said arm to rock it in the opposite direction.

3. An intermittent switch comprising a fixed contact, a balanced rocking arm having a contact carried thereon in position to move into contact with said fixed contact when said arm rocks in one direction, an electro magnet having an armature, a hammer actuated by said armature to kick said balanced rocking arm in a direction to move the contact carried thereon from contact with said fixed contact, a spring means pressing continuously on said balanced rocking arm to rock it in a direction to bring said contacts into contact, and an electric circuit comprising said contacts and said electro magnet in series.

4. An intermittent switch which comprises a fixed contact, a balanced rocking arm, a movable contact positioned to be moved into contact with said fixed contact when said arm rocks in one direction, an electromagnet having an armature,

a hammer actuated by said armature to kick said arm in a direction to move said movable contact into contact with said fixed contact and a spring acting continuously to rock said arm in the opposite direction to break the contact between said fixed and movable contacts.

JACQUES G. MEJEAN.
